DESIGN FOR A FOUR SPEED SAFETY MOTOR DRIVE

John Schultes and Vincent Schultes,
Detroit, Mich.

Application July 27, 1940, Serial No. 93,974

Term of patent 14 years

To all whom it may concern:

Be it known that we, John Schultes and Vincent Schultes, citizens of the United States, residing at 564 Bellevue Avenue, city of Detroit, in the county of Wayne and State of Michigan, have invented a new, original, and ornamental Design for Four Speed Safety Motor Drives, of which the following is a specification, reference being had to the accompanying drawings, wherein Figure 1 is a top plan view of a four speed safety

motor showing our new design; Figure 2 is an elevational view looking toward the handwheel end; and Figure 3 is a front elevational view thereof. The rear of the device is substantially similar to the front.

We claim:

The ornamental design for a four speed safety motor drive, as shown and described.

JOHN SCHULTES.
VINCENT SCHULTES.
